FIG.1

FIG.2

FIG.3

FIG.4

FIG. 1 is a top plan view of a combined hand grip and soap dish showing my new design;

FIG. 2 is a front elevational view thereof showing a portion of the soap dish in section and the vertical hand grip bar broken away to indicate indeterminate length;

FIG. 3 is a cross sectional view taken on line 3—3 of FIG. 2; and

FIG. 4 is a side elevational view of FIG. 2.

The fragmentary broken line representation on a wall in FIG. 4 is for purposes of illustration only.

We claim:

The ornamental design for a combined hand grip and soap dish, substantially as shown and described.
